UNITED STATES PATENT OFFICE

106,334

DESIGN FOR A COMBINED KITCHEN CABINET AND RANGE OR SIMILAR ARTICLE

Arthur P. Swanson, Des Plaines, Ill.

Application April 14, 1937, Serial No. 68,749

Term of patent 14 years

To all whom it may concern:

Be it known that I, Arthur P. Swanson, a citizen of the United States and a resident of the city of Des Plaines, in the county of Cook and State of Illinois, have invented a new, original, and ornamental Design for a Combined Kitchen Cabinet and Range or Similar Article, of which the following is a specification, reference being had to the accompanying drawing, forming a part thereof.

On the drawing:

I claim:

The ornamental design for a combined kitchen cabinet and range or similar article as shown.

ARTHUR P. SWANSON.
